UNITED STATES PATENT OFFICE.

FREDRICK S. DICKINSON, OF NEW YORK, N. Y.

DESIGN FOR A TIRE-CASING.

54,608.

Specification for Design.

Patented Mar. 9, 1920.

Application filed September 9, 1919. Serial No. 322,759. Term of patent 14 years.

To all whom it may concern:

Be it known that I, FREDRICK S. DICKINSON, a citizen of the United States, and resident of New York, in the county and State of New York, have invented a new, original, and ornamental Design for Tire-Casings, of which the following is a specification, reference being had to the accompanying drawing, forming part thereof.

Figure 1 is a plan view of a portion of the tread of a tire casing, showing my new design.

Fig. 2 is a cross-section on the line $x-x$, Fig. 1.

The features of my design comprise three parallel ridges, as shown at 1, extending circumferentially at the tread of the tire casing and having a plane surface, the two outer ridges being separated from the intermediate center ridge by grooves or depressions, as shown at 2, and the surface of said outer ridges being intersected by grooves or

depressions, as shown at 3, extending transversely of the ridge and diagonally or at an angle to the longitudinal plane thereof and intersecting the grooves or depressions 2, the terminal ends of said grooves or depressions 3 across the respective outer ridges being laterally broadened in a curved or spread formation, as shown at 4, which merges at one end into the groove or depression 2 at the side of the center ridge and at the other end into the side of the tread and forms a rounded or beveled contour at the corners of the plane-surface sections of the outer ridges which are intermediate of the transverse grooves or depressions 3.

I claim:

The ornamental design for a tire casing, substantially as shown and described.

In testimony whereof I have signed the foregoing specification.

FREDRICK S. DICKINSON.
